UNITED STATES PATENT OFFICE

101,220

DESIGN FOR A SHOE

Bennett Jayne, New York, N. Y., assignor to Bancroft-Walker Company, Waltham, Mass., a corporation of Massachusetts

Application July 16, 1936, Serial No. 63,880

Term of patent 3½ years

To all whom it may concern:

Be it known that I, Bennett Jayne, a citizen of the United States, residing at New York, in the county of New York and State of New York, have invented a new, original, and ornamental Design for a Shoe, of which the following is a specification, reference being had to the accompanying drawing, forming a part thereof, in which,

Fig. 1 is a plan view of a shoe showing my new design,

Fig. 2 is a view of the shoe in side elevation. In both figures the rear portion and the toe portion of the shoe are shown conventionally in dotted lines, the dominant feature of the design residing in the portion shown in full lines.

I claim:

The ornamental design for a shoe substantially as shown and described.

In witness whereof, I have affixed my signature hereto.

BENNETT JAYNE.
